UNITED STATES PATENT OFFICE.

CHARLES EDWIN KEFFER, OF MEMPHIS, TENNESSEE, ASSIGNOR OF ONE-HALF TO
OLIVER N. PRINCE, OF MEMPHIS, TENNESSEE.

TOY.

1,196,548.

Specification of Letters Patent.

Patented Aug. 29, 1916.

Application filed April 15, 1916. Serial No. 91,325.

To all whom it may concern:

Be it known that I, CHARLES E. KEFFER, a citizen of the United States, and a resident of Memphis, in the county of Shelby 5 and State of Tennessee, have invented a new and Improved Toy, of which the following is a full, clear, and exact description.

My invention relates to an animated toy 10 involving figures designed to represent two negroes in a butting match.

Objects of my invention are to provide a toy of the indicated character having simple and effective operating means to carry 15 the figures to and from each other, and to so arrange the members of the figures to give the impression of the figures taking a step to and from each other.

Other objects and advantages of the novel 20 construction will appear as the description proceeds.

Reference is to be had to the accompanying drawings forming a part of this specification in which similar reference characters 25 indicate corresponding parts in all the views.

Figure 1 is a longitudinal vertical section of a toy embodying my invention; Fig. 2 is a similar view with part of the cam 30 wheel broken away and with the parts in different positions from those shown in Fig. 1; Fig. 3 is a transverse vertical section on the line 3—3, Fig. 1; Fig. 4 is a horizontal section taken beneath the platform 35 and above the actuating mechanism. Fig. 5 is a face view of a modified form of cam wheel.

In constructing a toy in accordance with my invention, a hollow structure or stand 40 10 is provided, forming a casing for the actuating mechanism, the top 11 of which constitutes a platform. On the platform 11 near the ends, are posts 12 about which ropes 13 extend in simulation of the so-called pugilistic squared circle.

Above the platform 11, figures 14 are placed, and in practice, these will have the heads 15 inclined forwardly so that when the figures closely approach each other, they 50 will simulate the colliding movement of a butting match as practiced by negroes. The arms 16 preferably, are pivotally mounted to increase the action.

To support the figures, one leg 17 of each 55 figure is integral with the body thereof and

is rigidly supported on the upper end of a vertical pin 18, each pin 18 rising rigidly from a reciprocating block 19. The blocks 19 have dove-tail rear sides 20 having guided movement in dove-tail grooves 21 in a longitudinal member 22 in fixed relation to the casing 10. The two blocks 19 are connected at the under sides by a retractile spring 23, the ends of which are secured to screw eyes 24, or like means, on the respective blocks 60 19. The arrangement is such that any movement of one block 19 away from the opposite block, will place the spring 23 under tension so that its re-action will return the block thus moved.

To reciprocate the blocks 19, a cam wheel 25 is provided mounted on a transverse shaft 26, said shaft having a crank handle 27 at one end for turning the same. On the shaft 26 is a cam 28 disposed between the 70 blocks 19, the body of the wheel being of greater radius than the cam and overlapping the blocks 19. The width of the cam 28 is such as to be accommodated in recesses 29 in the faces of the blocks 19, the recess in 80 one block being at the top and the recess in the other block being at the bottom. The arrangement is such that as the wheel 25 is revolved by the shaft 26, the cam 28 will contact with the unrecessed portions of the 85 opposed edges of the blocks 19 and cause the said blocks to separate. Upon the nose of the cam coming opposite a recess 29 in a block 19, the spring 23 will force the recessed block forwardly. The continued 90 movement of the cam 28 gradually forces the opposite block 19 outwardly leaving the first block in the forward position for the time being. The result is that the figures 14 will follow the movements of the respective blocks 19 and be carried alternately forward so that each figure in succession gives a sudden butting movement.

The posts 12 in the forward and backward movements of the figures 14 and blocks 19, 100 move in slots 30 in the platform 11.

In order to give the figures the effect of taking a forward step, the one leg 31 of each figure is pivotally secured to the body as at 32 and the lower end is pivotally secured to a staple 33 or the like, in fixed position on the platform 11. Thus, the movement of the integral leg 17 of the figure will be to and from the pivoted leg 31.

Stop pins 34 are preferably employed be- 110

tween the blocks 19 to limit movement toward each other. In the illustrated construction, I have shown the shaft 26 having a collar 35, secured by a set screw 36 at the end of the shaft opposite the crank handle 27. The cam wheel 25 is shown as secured to the shaft 26 by a set screw 37. The shaft 26 has bearings in the casing 10 at opposite sides, and on said shaft, between the cam wheel 25 and the adjacent side of the casing, is a spacing sleeve 38.

In Fig. 5, the cam wheel, 25^a, has transverse pins 28^a in a side face thereof and disposed in a curve to constitute the cam.

15 Having thus described my invention I claim as new, and desire to secure by Letters Patent:

1. A toy of the class described including a supporting structure, figures oppositely disposed, a leg on each figure having a pivotal connection at its upper end with the figure and a pivotal connection at the foot with a relatively fixed part of said structure, blocks slidably supported in said structure below said figures to move to and from each other, the said figures having each a leg rigid with the figure and rigidly connected with the said blocks, a retractile spring connecting the said blocks, a wheel 20 mounted to turn in said structure and having a cam member disposed between the said blocks, said cam terminating in a lateral projecting nose, the said spring maintaining the blocks in contact with said cam, the said 25 blocks in their opposed ends having depressions, the depression in one block being at the top of the block and the depression in the other block being at the bottom of the latter, said depressions being adapted to 30 alternately accommodate the nose of the said cam, and stop pins on said structure adapted to be engaged by the respective blocks.

2. A toy of the class described including

a casing having a platform, figures oppositely disposed above said platform for movement to and from each other, said platform having slots therein beneath the figures, posts extending through said slots, the figures each having a leg rigid therewith, 45 said legs being rigidly connected with the respective posts, a leg on each figure pivotally connected at its upper end with said figure in the rear of the first leg, and pivotally connected at the foot member thereof with the said platform, blocks on which said posts are rigidly mounted, said blocks being slidable beneath the platform to and from each other, a spring connecting the said blocks, and a revoluble cam disposed 50 between the blocks and adapted to alternately move the same to and from each other.

3. A toy of the class described including a supporting structure, figures oppositely disposed, blocks slidably supported in said structure below said figures to and from each other, the said figures having each a leg rigid with the figure and rigidly connected with the said blocks, a retractile 65 spring connecting the said blocks, a wheel mounted to turn in said structure and having a cam member disposed between the said blocks, said cam terminating in a lateral projecting nose, the said spring maintaining 70 the blocks in contact with said cam, the said blocks in their opposed ends having depressions, the depression in one block being at the top of the block and the depression in the other block being at the bottom of the latter, said depressions being adapted to 75 alternately accommodate the nose of the said cam, and stop pins on said structure adapted to be engaged by the respective blocks.

CHARLES EDWIN KEFFER.
